UNITED STATES PATENT OFFICE.

CARL ALFRED LINDGREN, OF STOCKHOLM, SWEDEN.

DESIGN FOR A BOTTLE.

SPECIFICATION forming part of **Design No. 25,941, dated August 18, 1896.**

Application filed August 8, 1895. Serial No. 558,702. Term of patent 14 years.

To all whom it may concern:

Be it known that I, CARL ALFRED LINDGREN, a subject of the King of Sweden and Norway, residing at Stockholm, in the Kingdom of Sweden, have invented and produced a new and original Design for Bottles, of which the following is a specification, reference being had to the accompanying drawings.

10 Figure 1 is a side elevation of my design, and Fig. 2 is a plan view thereof.

The leading feature of my design is the configuration of the wall and neck of the bottle, as shown.

I claim—
15 The design for a bottle substantially as shown and described.

CARL ALFRED LINDGREN.
